UNITED STATES PATENT OFFICE.

CURT HILSCHER, OF CHEMNITZ, GERMANY.

THREAD-GUIDE ARRANGEMENT FOR COTTON KNITTING MACHINES FOR THE KNITTING OF STOCKINGS WITH TWO HEEL PARTS.

Application filed August 26, 1921. Serial No. 495,809.

To all whom it may concern:

Be it known that I, CURT HILSCHER, a citizen of the German Republic, residing at Chemnitz, Germany, have invented certain new and useful Improvements in Thread-Guide Arrangements for Cotton Knitting Machines for the Knitting of Stockings with Two Heel Parts (for which an application for patent has been filed in Germany on the 10 13th October, 1920), of which the following is a specification.

This invention relates to a device which, used in connection with Cotton knitting machines for the production of stockings with two heel parts, is designed to adjust automatically and to put in operation the thread guide required for the heel parts before the knitting of these heel parts is begun and, when the heel parts are finished, to stop these thread guides and to release the roll of fabric in order to cause the automatic detachment of the heel parts. The handwork which has been necessary up to the present and the stopping of the machine necessitated by this handwork are thus suppressed, wherefrom results an increase of efficiency of the machine.

The arrangement which has been made to solve this problem consists essentially in bringing the drive for the thread guide (the so-called brake) which is known by itself and which is controlled by a counting device, into the reach of a stop during an odd course, whereby this drive is properly adjusted upon the well known brake rod, auxiliary stops being further provided which are controlled also by the counting device and which determine the stroke of the thread guides in accordance with the said counting device.

In order to interrupt the displacement of the thread guides and of the taking up of the fabric when the heel parts have been finished a catch and at the same time a locking device are operated by one of the auxiliary stops, the catch serving to lock the rails of the thread guides and the locking device serving to release the roll of fabric from the action of the tension weight.

In order that the invention may be clearly understood, I shall proceed to describe the same with reference to the form of construction shown by way of example on the accompanying drawings, wherein:

Fig. 1 is a side elevation.

Fig. 2 and 3 are respectively a front view

and a plan view of the thread guiding device.

Fig. 3^a is a continuation of the right hand side end of Fig. 3.

Figs. 4 to 7 are detail views.

Fig. 8 illustrates the device for the detaching.

The construction of the device will be best explained by a description of the operation of the same which is as follows:

When the main thread guide II fixed upon the rail 2 (Figs. 1 and 3) has worked the legs L of the stockings up to the beginning of the heel parts F and F', its course having been the length W (Fig. 3), this course must be altered so that it is only equal to the length F of the right hand side heel part. At the same time a second thread guide I mounted upon rail 1 must be operated so that its course corresponds with the length F' of the second heel part. In order to ensure the operation of the thread guides I and II a so-called odd row is worked in the well known manner with the aid of a counting device. During the working of the odd row a lever 3 (Fig. 1), which up to this moment has been at rest, is released through the intermediary of the counting device so that this lever actuates in consequence of the action of a pull by means of a connecting rod 4 a lever system 5, 6, 7 so that the brake rod 8 is slightly turned and the catch 9 for the thread guide (brake) which is adjustably mounted upon said rod 8 is turned so that its dog 10 swings towards the thread guide rail 1. The dog 10 adopts thus the position shown on Fig. 4 in dotted lines, coming thus in reach of a fixed abutment 11 (Figs. 2 and 3) which locks the brake 9 so that its rod 8 is forced to shift for a distance x , the brake 9 altering thus its position upon said rod 8. A lever 12 (Fig. 1) which is controlled also from the counting device, is now operated by said counting device so that it adjusts, through the intermediary of the connecting rod 13 the angle lever 14 and pawl 15, a disk-shaped abutment 16 with abutment pins 17, 18, 19 in such a manner, that the pin 17 is brought over the rail 2 of the main thread guide II (Figs. 1 and 5). The displacement of the thread guide rail 2 is thus limited, in the left hand side direction, through the angle piece 20 of said rail coming in contact with the abutment pin 17, so that the course of the thread guide II is no longer equal to W (width of the leg of the stocking, Fig. 3)

but only equal to W' which is slightly longer than the width F of the heel, whereby the formation of proper border loops at the inner edge of the heel part F is ensured when the first row of heel loops is being knitted. When the knitting of the heel part F continues the course of the thread guide II is only W^2 as the abutment disk 16 is revolved again so that its pin 18 comes into reach of the thread guide rail 2 (Figs. 3 and 6) determining thus the limit of movement of said rail.

In order to throw in gear the thread guide rail 1 with the thread guide I an arm 21 whose screw bolt 22 has served as abutment for the carriage 9 (Figs. 1 and 3) is raised so that the dog 10 comes in engagement with the fork 23 fixed upon the rail 1 and can thus draw along this rail. A lever 24 designed for the automatic adjustment of this arm 21 is controlled also from the counting device, its movement being transferred to arm 21 by means of levers 25, 26 and 27.

The adjustments described have been made during the working of the odd row from right to left. If now the loops of the first row of heel loops are sunk from left to right both thread guides I and II run only so far as is necessary for the required width of the heel parts, the well known set on frame 28. (Figs. 2 and 3) which is loosely mounted upon the thread guide rail 1 dropping at the same time in consequence of the displacement of the said rail 1 to the right, and adjusting itself so that its stop screw limits the course of the thread guide at the left hand edge of the heel part F' . During the knitting of this row the abutment disk 16 is revolved again so that it gets from the position Fig. 6 to the position Fig. 7, its pin 19 serving now to stop the movement of the thread guide at the inner edge of the heel part F . The said heel parts are completed with the adjustments described.

When, after the heel part is finished, the detachment of the same from the knitting needles has to be effected, the abutment disk 16 is revolved again when the last row of heel loops is being knit, so that a segment 30 fixed upon said disk (Fig. 8) adopts such a position that the nose of a lever 31 which rests upon this segment drops into a notch of said segment so that an arm 32 pivotally fixed upon the pivot pin of said lever 31 drops down upon the thread guide rails and locks the same so that they can not be moved when the next row of loops is being sunk, wherefrom results the detachment of the

heel parts as the thread is not conducted to the needles. In order to neutralize the action of the well known tension weight upon the roll of fabric, the lever 31 operates at the same time a lever 33 so that its locking pawl 34 engages with a ratchet wheel 35 of the bobbin 37 which is thus prevented from being revolved by the tension weight 38.

I claim:—

1. Thread guide arrangement for Cotton knitting machines for the knitting of stockings with two heel parts, comprising in combination with the main thread guide for the production of one of the heel parts and its rail, with means for operating said thread guide rail and said mechanisms adapted to be controlled by a counting device, a second thread guide rail with a thread guide for the production of the second heel part, an abutment disk adapted to be controlled from said counting device for automatically adjusting and operating said main thread guide rail and an arm pivotally fixed upon the axle of said abutment disk and adapted to be controlled from the said counting device for automatically adjusting and operating the said second thread guide rail.

2. Thread guide arrangement for Cotton knitting machines for the knitting of stockings with two heel parts, comprising in combination with the main thread guide for the production of one of the heel parts and its rail, with means for operating said thread guide rail and said mechanisms adapted to be controlled by a counting device, a second thread guide rail with a thread guide for the production of the second heel part, an abutment disk adapted to be controlled from said counting device for automatically adjusting and operating said main thread guide rail, an arm pivotally fixed upon the axle of said abutment disk and controlled from the said counting device for automatically adjusting and operating the said second thread guide rail, and a catch operated from said abutment disk for locking the thread guide rails in order to detach the finished heel parts by the interruption of the displacement of the thread guides.

In testimony, that I claim the foregoing as my invention, I have signed my name in presence of two subscribing witnesses.

CURT HILSCHER.
